UNITED STATES PATENT OFFICE.

LOUIS STEINBERGER, OF BROOKLYN, NEW YORK.

INSULATOR.

1,072,524.

Specification of Letters Patent.

Patented Sept. 9, 1913.

Application filed September 21, 1910. Serial No. 533,625.

To all whom it may concern:

Be it known that I, LOUIS STEINBERGER, a citizen of the United States, and a resident of the city of New York, borough of Brooklyn, in the county of Kings and State of New York, have invented a new and Improved Insulator, of which the following is a full, clear, and exact description.

My invention relates to an insulator to be used in connection with high potential electric conductors employed for various purposes, such as power transmission, wireless telegraphy and telephony, and ordinary commercial service of various kinds.

In my new system I employ a number of individual insulating units of different character. By aid of my improved weather shields, herein described, I am enabled to render the individual units of comparatively small size, light weight and low cost, as well as adapting the units for carrying currents of exceptionally high potential.

My invention is adapted for limiting leakage and preventing undesirable grounding of the current, either from conductors or from structures employed for supporting conductors.

My invention also tends to prevent arcing and puncturing of the various individual units.

Generally speaking, my system comprehends a plurality of cross-bar tubular insulators with or without weather shields, and a plurality of hood or disk type insulators, also with or without weather shields and suspended from a support.

It will be understood that in some instances I may dispense entirely with the hood or disk type insulator units and employ only the cross-bar type, disposed in relation to each other in any preferred manner.

While in the drawing I show a metal rod extending through the cross-bar member, in other instances I may employ a rod of fiber, hard rubber or other suitable insulating material. Also, the cross-bar member may be of a solid single mass of material. Again, two rods or bolts may be used, each extending into the ends of the member, only a short distance and insulated from each other.

The complete structure, comprising a flexi-

ble chain made up of several units, may be extended indefinitely and the degree of insulation afforded by the chain may be increased correspondingly. Moreover, the various parts may be readily detached and replaced by other parts, and the total number of parts may be increased or diminished at will after the original structure is finished. This feature I regard as especially important in instances where, after the installation of the system, the voltage of the currents is to be increased. My invention is readily adapted for increase, to any desired extent, in the voltage, the various mechanical parts which I employ being of comparatively simple form, small size, light weight and low cost.

My invention further comprehends the protection of the various individual units from rain, snow and sleet; also the prevention of short circuits otherwise caused by streams of water during heavy rain storms carrying the current from one unit to another. My invention thus prevents serious leakage and danger of arcing of the current, and as a result avoids damage to or destruction of the various insulator units. Hence, my system at all times affords adequate insulation for all practical purposes.

In addition to the foregoing, my invention contemplates various improvements in the specific kinds of insulator units comprising my system.

Among the several objects of my invention are the following: I. To protect the individual units from rain, snow and the like, thereby enabling me to employ units of small size for carrying currents of high potential. II. To divert the arc from a practically straight course, thereby tending to subdivide or break up the arc and thus prevent its destructive effects. III. To avoid the formation of conductive paths between units otherwise caused by the dripping or running of water from one unit to another. IV. To give the various parts such conformity as will tend to prevent the creepage of moisture, and by so doing to prevent arcing or puncturing, under the influence of currents of high voltage. V. To provide units containing conducting members extending in the general longitudinal direction of such units and having the portions extending from

each end of the unit for the purpose of attaching other conducting members in order to form a chain. VI. To provide improved units having distinct portions for insulating purposes and for diverting moisture from said insulating members, one of said portions being adjustable relatively to the other. VII. To provide a unit having a plurality of tubular members disposed concentrically and comprising an inner member made of strong and tough non-fireproof material, and an outer member made up of a brittle but fireproof material, such as porcelain, glass or the like. VIII. To prevent the line from falling in the event that the insulation of the chain of units, or any part thereof, becomes injured or destroyed. IX. To provide an improved form of units which, when connected together in a chain will admit the addition of other units for the purpose of increasing the aggregate degree of insulation afforded. X. To provide improved forms of units with means for locking said units in predetermined positions relatively to their supporting means. XI. To provide the various units with strengthening members disposed within them. XII. To connect a number of hood or disk type insulator units and cross-bar type of insulators, the cross-bar insulators being disposed perpendicularly in relation to the axes of the hood or disk types of insulators. XIII. To build up a chain of improved insulator units each having such form that it may be removed from said chain and used as an individual insulator. XIV. To provide an improved form of cross-bar insulator having a plurality of annular grooves and a plurality of annular ridges with sharp edges, for the purpose of allowing moisture to drip off quickly, and also for preventing dust from lodging on said ridges. XV. To increase the resiliency of the system as a whole, by the use, between insulating units, of springs of special adaptability for this purpose. XVI. To provide a unit made up of a plurality of insulating members, one sleeved over the other, and of the same or different materials, thereby largely increasing the factor of safety; for instance, in the event of cracking or destruction of the outer member, the inner member or members will still support and insulate the line. All of the members may be of "electroso," or they may be made of electroso and porcelain, or electroso and hard rubber or fiber, or of any other suitable insulating material. XVII. To connect a number of cross-bar insulator units disposed horizontally in relation to each other or horizontally and vertically as may be most advantageous or desirable. XVIII. To connect a hood or disk type unit and a cross-bar type unit, the cross-bar type unit depending from said hood or disk type unit and being disposed with its longitudi-

nal axis arranged perpendicularly to the axis of the hood or disk type unit.

Reference is to be had to the accompanying drawings forming a part of this specification, in which similar characters of reference indicate corresponding parts in all the figures.

Figure 1 is an elevation showing my system complete and used, in this instance, for suspending a conductor shown at the bottom of the figure; Fig. 2 is a section on the line 2-2 of Fig. 3, looking in the direction of the arrow and showing some of the units contained in my system; Fig. 3 is a section on the line 3-3 of Fig. 2, looking in the direction of the arrow, and showing the same mechanism as said figure; Fig. 4 is a plan view of one of the weather shields and the tubular support integral with it, whereby it is suspended; Fig. 5 is a perspective showing a tubular insulator and parts accompanying the same, used as indicated at the bottoms of Figs. 2 and 3; and Fig. 6 is a perspective of the insulator tube alone.

A disk shaped hood or shield 7 is provided with a thick central portion 8 and embedded within this thick portion is a basket 9 having upon it, and integral with it, an arched portion 10, the latter being provided with a threaded boss 11 projecting above the upper surface of the hood. The basket 9 is of a general annular form and extending through it is a screw bolt 12. This screw bolt is provided with a frusto-conical head 12^a which prevents it from being drawn through the opening in the basket 9. A clamp 13 is made in halves which are provided with ears 14, and engaging these ears are screws 15 for holding the two halves of the clamp together. The screw 12 projects below the under surface of the hood and into threaded engagement with the upper portion of the clamp 13, whereby said clamp, and the parts supported thereby, are permitted a desirable degree of rotary movement relatively to the hood. At 16 is a link made of a piece of twisted wire cable formed into a loop, the ends of the cable being twisted together and adjustably held by pressure of the clamp 13. At 17 is a disk insulator which is provided centrally with a depending body portion 18 integral with it. Encircling this body portion and integral with the disk 17 is a collar 19 having a general annular form.

The body portion 18 is provided with an opening 20 extending diametrically through it, as shown more particularly in Figs. 2 and 3. Extending through the opening 20 is a link 21 formed of a section of flexible wire cable, the ends of which are twisted together and adjustably held by aid of a clamp 22. This clamp is made in halves provided respectively with eyes 23 through which extend screw bolts 24. The clamp 22 is

formed with a depression 22^a and extending through this depression is a bail 25 having eyes 26 and also having spring portions 27. These spring portions are bent back upon themselves, as indicated, and are thus given proper conformity to serve as leaf springs. A metallic rod 28 extends through the eyes 26 and is provided with threaded ends 29 upon which are screwed nuts 30. The bail 25 is preferably divided at its middle and the two parts thereof are separably connected at the point of the clamp 22, as by a bolt 24^a, so that the bail, and parts suspended therefrom, may be readily detached when desired. The twisted wire, comprising the loop or link 16, is molded within the body portion 18 of the insulator 17 and the lower portion thereof encircles the opening 20, being spaced therefrom at all points by a sufficient bulk of insulating material to avoid all possibility of arcing. The exposed portions of the wire between the clamp 13 and insulator 17 provide a certain degree of flexibility between said members as will be apparent.

The insulator 17 is of a somewhat smaller diameter than the hood 7 and the upper surface thereof is convexed so as to deflect water away from the metallic parts, and the under surface of the hood is recessed sufficiently to receive the major portion of the insulator, and said insulator being thus nested within the hood, its upper surface is quite effectually protected.

Supported by the bail 25 is a rain shield having generally the form of a shed and provided with ends 33 sloping obliquely downward to facilitate the shedding of moisture. This rain shield is provided with a tubular portion 32 through which the rod 28 extends. The ends of the tubular portion serve as limiting stops against which the eyes 26 are pressed by action of the nuts 30, and said tubular portion serves as a spacer for the intermediate portions of the bail 25 at the upper ends of the spring portions 27. The spring portions 27 are provided with eyes 34 which are disposed adjacent to the respective ends of a tube 35. This tube 50 may be of porcelain, glass or other brittle material and is provided with corrugations 36 integral with it, and each of a general annular form and having sharp edges. A metallic collar 37 is fitted upon the tube 35 midway of the ends thereof in a seat 38 provided for the purpose. The ends of this collar hang downwardly and extending through them is a pin 39. A tube 40 of electrose, hard rubber or other high grade insulating material, is disposed within the tube 35 and concentric relatively to the same. Extending axially through the tube 40 is a metallic rod 41 provided with threaded ends 42 upon which are fitted nuts 43. The eyes 34 of the spring portions 27 are fitted upon the ends of the rod 41 and are pressed toward each other by the nuts 43, so as to clamp them rigidly in relation to the tubes 35, 40.

The composite insulator, made up of the insulators 35 and 40, I desire, for convenience of distinction, to term a cross bar insulator, which term may also include broadly the shield 33 and bail 25—27.

Where it is desired to use insulator units of the kind shown in Fig. 2, and below these units to employ a rod type insulator, the parts are arranged as indicated in the lower portion of Fig. 1. A bolt 44 is threaded through an eye 45, this eye being secured in the upper end of a rod type insulator 46 provided with corrugations, as shown. The lower end of this rod type insulator is provided with an eye 47 carrying a clamp 48 which supports a conductor 49.

I find that a very good arrangement of the insulator units above described is that shown in Figs. 1 and 2. Here the uppermost insulator 17 is of the disk type with the protecting hood 7, having a suitable suspending means threaded upon the boss 11 thereof, and the insulator 17 and hood 7 being flexibly connected together. Suspended from the middle or body portion of the insulator 17, by aid of the flexible link 21, bail 25, and rod 28 is a cross-bar type insulator with rain shield 31. Next below is another disk type insulator with its hood and below this is another cross-bar insulator. A series may thus be continued indefinitely. In the lower part of Fig. 1, however, I do not use any disk type insulators and merely connect up a number of the rain shields and insulators of the cross bar type. The lowermost unit of my system is the vertically disposed rod type insulator 46. The spring portions 27 give the system considerable resilience, because a slight yielding upon the part of a considerable number of the insulating units enables the conductor 49 to have considerable freedom of movement. Again, the system has considerable flexibility, due to the fact that the various flexible links made of twisted wire cable allow of considerable bending in the system as a whole without the necessity for any one of these links being bent to excess. It will also be noted that the weight of the rain shield 31 is distributed with approximate uniformity throughout practically the entire length of the rod 28, so that the weight of the rain shield, though hanging upon this rod, will have no undue tendency to break or bend the rod or to subject any portion of the tubular member 32 to excessive strain. Again, because of the resiliency afforded by the spring portions 27, the metallic rod 41, and the tubes 35, 40 which it carries, are subject to such conditions that all mechanical strains upon them are dispersed.

tributed as nearly equal as possible. The corrugations 36 tend to prevent the travel of moisture along the tube 35, if, indeed, any moisture succeeds in reaching any portion of this tube. The downwardly sloped portions 33 of the rain shield, by guiding the rain obliquely downward and away from the center of the system, tend, in a measure at least, to prevent the rain water from reaching the tube 35, and should a few drops accidentally obtain access to this tube the dry spaces between the corrugations 36 prevent leakage of the current along the surface of the tube 35. The spring portions 27 have their ends inclined upwardly toward the nuts 43 so that any water falling upon said inclined portions, from the parts 33 of the shield 31, or otherwise, will be led directly away from the nuts.

20 By connecting a number of insulator units of the same kind in series with each other, as shown in the lower middle portion of Fig. 1, or by alternating with disk and cross-bar types, or by employing a series of only 25 the disk type insulators, the insulating strength of the system as a whole may be increased at will. The vertical rod type insulator 46 with its corrugations serves to still further increase the insulating value 30 of the system as a whole. This rod type insulator is of a diameter which is small as compared with the length or width of the shields 31, or the diameter of the disks 7. The advantage of this is that in case the 35 wind blows against the chain of insulators and causes the same to swing, there is less liability for any part to strike a neighboring object if the diameter of the rod type insulator 46 (that is, the insulator nearest the 40 conductor 49) be small.

The system as a whole may be used effectively without employing any of the rain shields, though it is self evident that a larger factor of safety is provided and insulators of smaller sizes may be employed 45 when rain shields are used with the system.

From the foregoing it will be apparent that there is a metallic chain extending 50 throughout the length of the several units in such manner that if any portion of the insulating material comprising the units is broken or destroyed, said metallic chain will be effective to form a positive support for 55 the conductor 49; for instance, if the insulator 17 be destroyed through disintegration or otherwise, the loop 21 will come to rest within the pocket formed by the loop 16; and likewise, if the composite insulator 60 35-40 be destroyed, then the collar 37 will come to rest in contact with the rod 41. It will be noted also that throughout the greater portion of its extent the under surface of the hood 7 is in relatively closed 65 juxtaposition to the upper surface of the

insulator 17, and that centrally above the insulator 17 the hood is formed with a pocket which serves not only to accommodate the clamp and other metallic portions extending between the insulator and hood, 70 but also to contain a dry dead air, which will be effective in repelling the advance of moisture laden air upward through the relatively small opening between the outer portions of the insulator and the hood. It is 75 also apparent that the loop 16 not only serves to reinforce the body portion of the insulator 17, but, that, from its twisted formation, it is slightly elastic, enough so as to absorb sudden violent mechanical shocks 80 and thus often serve to save the insulator from destruction.

I do not limit myself to the particular shape or form for any part shown. Neither do I limit myself in all instances to the precise arrangement of the parts relatively to each other; nor to the employment in every instance of weather shields on all of the units or on any of them; nor do I limit myself to any particular material or materials to be used in my system, or in the construction of any of the units thereof. I prefer, however, to employ for the various insulating parts, the material known in this art as "Electrose." For the tube 35, however, I may at times employ porcelain or glass, or such like material. For the metallic parts I generally prefer steel, though other metals may be used with success.

Having thus described my invention, what 100 I claim as new and desire to secure by Letters Patent, is:

1. Insulating means, comprising a support, a bail suspended therefrom, a rain shield mounted between the legs of said bail, 105 and an insulator mounted within said rain shield.

2. Insulating means, comprising a bail provided with spring portions, a rod extending from one part of said bail to another part thereof, and a rod type insulator 110 connected with said spring portions.

3. Insulating means, comprising a bail provided with eyes and with spring portions, said spring portions having eyes, a 115 rain shield provided with a tubular portion disposed between said eyes of said bail, and an insulator supported by aid of said eyes of said spring portions, said last mentioned insulator being sheltered by said rain shield. 120

4. Insulating means, comprising a rain shield provided with a tubular portion integral therewith, a rod extending through said tubular portion, a bail provided with portions connected with the ends of said rod, 125 means for supporting said bail, and an insulator mounted within said rain shield.

5. Insulating means, comprising a rain shield provided with a tubular portion integral therewith, a rod extending through said 130

- tubular portion, a bail provided with portions connected with the ends of said rod for supporting said rod, and an insulator flexibly supported below said rain shield.
- 5 6. Insulating means, comprising a rain shield provided with a tubular portion integral therewith, a rod extending through said tubular portion, a bail provided with portions connected with the ends of said rod for 10 supporting said rod, and an insulator mounted upon said bail suspended below and partially within said rain shield.
7. Insulating means, comprising a rain shield provided with a surface for shedding water in two directions, and further provided with sloping ends for shedding water in two other directions, said rain shield being also provided with a tubular portion, a rod extending through said tubular portion, means for supporting said rod and thereby sustaining said rain shield, and an insulator suspended within said rain shield and sheltered thereby.
8. Insulating means, comprising a rain shield provided with a tubular portion integral with it, a rod extending through said tubular portion for supporting the rain shield, an insulator sheltered by said rain shield, and mechanism connected with said 25 rod for supporting said insulator relatively to said rain shield.
9. Insulating means, comprising a rain shield provided with shoulders, a bail provided with eyes engaging said shoulders and further provided with spring portions, said 30 spring portions being bent so as to reach underneath said rain shield, and an insulator engaging said spring portions underneath said rain shield.
- 40 10. Insulating means, comprising a rain shield, an insulator having the form of a cross-bar, and a single means for supporting said shield and for resiliently supporting said insulator below said shield.
- 45 11. Insulating means, comprising a rain shield, means for suspending the same, spring members connected with said rain shield and bent to extend underneath the same, and an insulator mounted upon said 50 spring members.
- 55 12. Insulating means, comprising a rain shield, spring members connected with said rain shield and bent to extend therebelow, and an insulator extending from one of said spring members to another and being thus supported resiliently.
- 60 13. Insulating means, comprising a rain shield having an oblong form, and disposed horizontally, and a rod type insulator disposed horizontally below said rain shield, the length of said insulator being parallel with that of said rain shield, and means for supporting said insulator resiliently within said rain shield.
- 65 14. Insulating means comprising a rain shield having an elongated form, and disposed horizontally, a rod type insulator, also disposed horizontally, the length of said insulator being parallel with that of said rain shield, and means for supporting said insulator by its ends beneath said rain shield.
- 70 15. Insulating means comprising a rain shield, a rod type insulator disposed beneath said rain shield, means supporting said insulator from said rain shield, a member encircling said insulator at its proximate middle, and mechanism connected with said last named member for sustaining a conductor.
- 75 16. Insulating means comprising a rod, and supporting means therefor, a tube of high grade insulating material encircling substantially the entire cylindrical surface of said rod, and another tube encircling said first mentioned tube and made of insulating material of a different character and provided with corrugations.
- 80 17. Insulating means, comprising a horizontally disposed insulator, a horizontally disposed member for supporting the same, and a spring member connected to each end of said horizontally disposed insulator.
- 85 18. Insulating means, comprising a rain shield, means for supporting the same, spring members connected with said rain shield, and an insulator mounted upon said spring members.
- 90 19. Insulating means, comprising a longitudinal insulator, a longitudinal rain shield therefor, and spring suspension means engaging the ends of both the rain shield and insulator.
- 95 20. A device of the kind described, comprising an insulator member, and a spring suspension therefor having downwardly and outwardly inclined portions fixed to said insulator and extending therefrom so as to conduct moisture away from said insulator.
- 100 21. A device of the kind described, comprising a cross bar insulator member, and a spring suspension therefor having downwardly and upwardly inclined portions fixed to opposite ends thereof and extending therefrom so as to conduct moisture away from said insulator.
- 110 22. A device of the kind described, comprising an insulator member; a shield therefor; and means extending upon opposite sides of said insulator and shield for retaining insulator and shield in coöperative relation.
- 115 23. A device of the kind described, comprising an insulator member; a shield therefor; and means extending upon opposite sides of said shield, having upturned portions engaging said insulator member.
- 120 24. Insulating means, comprising a longitudinal insulator, a horizontally disposed

member for supporting the same, and a spring member connected to each end of said horizontally disposed member.

25. Insulating means, comprising a longitudinal insulator, a horizontally disposed member beneath which said insulator is supported upon supports comprising spring parts extending from the opposite ends of said member into engagement with the adjacent respective ends of said insulator.

26. Insulating means, comprising a longitudinal insulator, and a pair of members attached one to each end of said insulator, extending outwardly from said ends, and each being bent upon itself so as to form a spring support for said insulator.

27. Insulating means, comprising a bail provided with spring portions, and an insulator connected to said spring portions.

28. Insulating means, comprising a bail having its ends bent to form springs, and an insulator connected to said springs.

29. Insulating means, comprising a bail having oppositely disposed legs, an insulator supported between said legs, and one of said legs having a resilient portion to which the insulator is connected.

30. Insulating means, comprising a bail having portions of its legs projecting away from each other, said portions being bent

upon themselves toward each other so as to form springs, and an insulator connected to said springs.

31. Insulating means, comprising a bail having the end portions of its legs spaced apart, said end portions being bent to project away from each other and being further bent upon themselves toward each other so as to form springs, means extending between said end portions for holding them spaced, and an insulator connected to said springs.

32. Insulating means, comprising a bail provided with spring portions, and a rod type insulator extending between and being connected by its ends to said spring portions.

33. A device of the kind described comprising a rod type insulator, and a support therefor, formed of a leaf spring having its ends bent into engagement with the opposite ends of the insulator.

In testimony whereof I have signed my name to this specification in the presence of two subscribing witnesses.
